UNITED STATES PATENT OFFICE.

STANLEY PIUT, OF GLEN RICHEY, PENNSYLVANIA.

CARBID-LAMP.

1,281,651.

Specification of Letters Patent. Patented Oct. 15, 1918.

Application filed March 19, 1918. Serial No. 223,376.

To all whom it may concern:

Be it known that I, STANLEY PIUT, a citizen of the United States, residing at Glen Richey, in the county of Clearfield and State of Pennsylvania, have invented certain new and useful Improvements in Carbid-Lamps, of which the following is a specification.

The invention has for an object to provide a simple and economically manufactured form of acetylene generating lamp suitable for use upon bicycles and motor vehicles. A particular purpose is to give a satisfactory structure in such lamps which is adapted to be started quickly, and in which the renewal of water and carbid may be accomplished with facility.

Additional objects, advantages and features of invention will appear from the construction, arrangement and combination of parts hereinafter described and shown in the drawings representing one of the possible embodiments of my invention, wherein—

Figure 1 is a vertical sectional view of a lamp constructed in accordance with my invention,

Fig. 2 is an enlarged view of the construction of the regulator parts,

Fig. 3 is a fragmentary top view.

There is illustrated a lamp comprising an upper reservoir and headlight construction 30, which includes a body portion 11 of substantially cylindrical form, disposed upon a horizontal axis, the side portion and rear end portion 12 being pressed integrally from one blank of plastic metal. The front end of the receptacle is closed by means of a reflector element 13 fitted snugly therein, a suitable lens 14 being held over the end of the receptacle which projects some distance 40 beyond the reflector 13, by means of a screw cap 15.

Any suitable means is provided at 16 for mounting the lamp upon a bracket, this mounting being secured upon the rear end 45 12 of the reservoir receptacle.

A tubular stem 17 is secured upon the lower side of the receptacle 11 having threads thereon, and upon this there is engaged an interiorly threaded neck portion 18 50 of the carbid container 19 which may be of any familiar construction, in the present instance shown as substantially bottle-shaped, including the neck portion 18.

From the upper part of the stem 17 a 55 suitable pipe 20 leads to the space immediately before the reflector 13, the outer

end of the pipe being provided with a suitable burner 21.

Through the lower side of the receptacle 11 there is extended a water feed pipe 22, 60 which also extends upwardly across the reservoir to a movable spring mounting subsequently to be described. This pipe is provided with suitable apertures therein adjacent the lower part of the receptacle 11, and 65 may also have a suitable wick 23 therein. It is considered desirable that this pipe may be constructed so that its upper end may move vertically, for opening and closing of the upper end thereof as will be subsequently 70 described, and in order to facilitate this, the pipe may be shaped as shown at 24, including a helix, or it may be made in two sections connected by a small piece of rubber tubing or the like, the last named detail not 75 being illustrated, as being sufficiently obvious.

The upper end of the pipe 22 is secured upon the end of a small spring 25, which in turn is mounted upon a heavier spring 26, 80 secured to the inner side of the receptacle 11 at its upper part. For the proper functioning of the device the heavier spring 26 is apertured to permit the pipe to pass therethrough freely for vertical movement the 85 spring 25 being attached to the larger spring adjacent the swinging end of the latter, extending inwardly thereover. The larger spring is the heavier or stronger of the two, for reasons which will become apparent. On 90 the outer end of the spring 26 a valve seat 27 is mounted, adapted to seat in an opening 28 in the upper side of the receptacle 11 when the spring 26 is at the upper limit of its movement. A small push button 95 29 is mounted upon the spring 26, and located without the receptacle 11, pressure upon which will depress the spring 26, moving the valve 27 to open position, as will readily appear. The button 29 may be 100 mounted upon the valve 27, by means of a very small stem 30, so that when the valve is open the stem of the button 29 does not materially diminish the clear way through the opening. Upon the top of the receptacle 110 11 a small annular seat 31 is provided, and the upper end of the pipe 22 is constructed to engage snugly around this seat, the receptacle 11 having a suitable opening therethrough leading through the opening in the seat 31. Upon the outer side of the receptacle 11 a regulator valve is provided, in

the form of a small spring 32, having its free end adapted to fit snugly over the opening in the receptacle 11 to the seat 31. The spring 32 is secured pivotally upon the receptacle 11, so that it may be moved to one side, to regulate the amount of air which may pass through the seat 31, to permit proper feeding of water from the receptacle 11 to the carbide container 19, as will become apparent. The pipe 22 is provided with holes 33 adjacent its lower end through which water in the receptacle may gain access to the wick 23, and if desired additional holes 34 may be formed in the upper part of the pipe through which air drawn through the seat 31 may gain access to the upper part of the receptacle 11.

In use, the carbide container 19 being properly filled and the receptacle 11 partly filled with water, when it is desired to start the lamp, in order to avoid delay in waiting for the generation of sufficient pressure in the carbide container to supply gas as desired to the burner 21, the button 29 is depressed, which admits a large quantity of air directly to the container 11, permitting a rapid flow of water from the container through the pipe 22 to the carbide, and after depression of the button 29 for a short time, it is released, and the lamp allowed to operate automatically, the flow of water from the receptacle 11 to the container 19 being regulated by means of the valve 32.

The receptacle 11 may be provided with a customary form of filling opening and closure as at 36.

What is claimed:

1. A lamp of the character described comprising a carbide receptacle a water receptacle, a feed pipe leading from the water receptacle to the carbide receptacle, said pipe having a portion longitudinally movable, an annular seat adapted to engage the movable

end of the pipe at one limit of its movement, resilient means tending to keep the pipe seated, means to admit air through said seat, and to regulate the flow of air therethrough, said resilient means including also a valve mounting, an opening in said receptacle adjacent said mounting, a valve on the mounting movable for engagement in said opening when the pipe is engaged with said seat, means to move the valve and pipe simultaneously for unseating, for the purposes described. 50

2. A lamp of the character described comprising a water receptacle a carbide receptacle detachably mounted thereon, means to conduct gas from the carbide receptacle, said receptacle having a top portion, a heavy spring mounted thereon tending to movement toward the top, an air vent opening in said top, a valve on said spring adapted to engage said openings, a second opening in the top, a light spring mounted upon the first mentioned spring and tending to bear against the top adjacent said opening when the first mentioned spring is at one limit of its movement, means to regulate passage of air through said opening, a pipe element having a flexible portion, the upper end of said pipe being mounted upon said second mentioned spring, a seat being formed around said opening for snug engagement with the upper end of the pipe when at the upper limit of its movement, means to depress the first mentioned spring for unseating of the valve and pipe, and said pipe having openings in its upper and lower part for the purposes described. 70

In testimony whereof I have affixed my signature in presence of two witnesses.

STANLEY PIUT.
